MATCH-MACHINE.

SPECIFICATION forming part of Letters Patent No. 757,572, dated April 19, 1904.

Application filed September 21, 1901. Serial No. 76,021. (No model.)

To all whom it may concern:

Be it known that I, MARK A. SHELDON, a citizen of the United States of America, residing at Detroit, in the county of Wayne and State of Michigan, have invented certain new and useful Improvements in Match-Machines, of which the following is a specification, reference being had therein to the accompanying drawings.

10 This invention relates to match machinery of that character in which wholly independent plates or racks are used for holding the match-splints, which plates or racks after being first provided with splints by independent and separate devices are then transferred to a match-making machine which has a suitable carrier for carrying the plates automatically through all the different operations needed to make the finished matches, after which the plates 20 must be replenished again with fresh splints by the independent devices aforesaid.

It is the object of my invention to improve upon this mode of operation in so far as to make the replenishing of the empty plates with 25 fresh splints and their delivery to the carrier for treatment a part of the operation of the machine itself without losing any of the advantages incident to the use of independent plates.

30 To this end my invention consists in an automatic plate-feeder and involves as a new feature a magazine in which the empty plates are stored, a subcarrier separate and independent of the main carrier of the machine 35 and adapted to automatically remove the plates one by one from said magazine and deliver them automatically to the main carrier, and a suitable splint-feeding device operating in connection with said subcarrier to replenish each 40 plate with fresh splints while in transit between the magazine and the main carrier, all as more fully hereinafter described, and shown in the accompanying drawings, in which—

Figure 1 is a vertical central section of my 45 automatic plate-feeding device. Fig. 2 is a side elevation thereof. Fig. 3 is a rear elevation of the magazine. Fig. 4 is a cross-section on line $\alpha\alpha$, Fig. 1.

In the drawings the match-machine to which

my plate-feeding device is intended to apply 50 is merely represented by its carrier, which consists of a pair of drag-chains A, provided at intervals with lugs B and adapted to drag the plates P along during the treatment of the splints by engaging into slots a in the marginal outer portion of the plates, the plates having the usual perforations for holding the splints, all as well known.

C is a magazine for holding plates. It is open in front for the insertion of the plates 60 and is formed with two vertical sides b and an inclined shelf or bottom c , upon which the plates are adapted to be supported in upright position by the weight of the plates causing them to slide down upon the inclined bottom 65 and by the action of a gravity-dog D, pivotally secured in the upper part of the magazine and pressing the plates against the vertical stops or guides d upon the rear of the magazine. The gravity-dog D is made in the 70 form of a bell-crank with a long weighted arm projecting outwardly and serving as a handle, the other arm being curved to project downwardly and rearwardly, all in such manner that it will hold a varying number of 75 plates in position in the magazine and permit the insertion of fresh plates by throwing up the dog.

E is a slide in the bottom of the magazine, terminating at its rear end in an upturned 80 flange or lip e , adapted to engage the lower edge of the plate at the foot of the incline in such manner that by drawing out the slide it will draw the plate for a purpose which will appear more fully hereinafter.

F F are two drag-chains which form the subcarrier for feeding the plates one by one from the magazine to the main carrier. These drag-chains are both in the same vertical plane with the plane of the plate which is at 90 the foot of the incline, and each chain has corresponding lugs f , adapted to engage with the plates and carry them upward. The drag-chains pass around sprocket-wheels g , secured upon horizontal shafts g' , which are journaled 95 in suitable bearings upon the sides of the magazine, and the lower set of shafts has intermeshing gear-wheels g^2 for simultaneously

imparting motion to the drag-chains through a ratchet-wheel g^3 , secured upon one of the shafts and receiving intermittent motion through the feed-pawl g^4 and connecting-rod g^5 from any suitable moving part of the machinery, the drawings showing it as receiving power from the drive-shaft g^6 of the splint-feeding device through the crank g^7 , to which the rod g^8 is connected. The plates P are cut away at the corners to form shoulders h for the engagement of the lugs f of the drag-chains, the distance between the lugs being equal to the length of the plates.

The drag-chains F form a relatively short carrier able to carry but a few plates at a time, one following the other closely, and while thus in transit the plates receive splints from a splint-feeding device G , placed in position to stick rows of splints into each plate as it travels past it, the travel of the carrier being so adjusted and timed with the movement of the splint-feeding device that each row of perforations in the plates has a row of splints stuck into it endwise as it passes the device. As the construction and operation of such splint-feeding devices are well known and understood to those skilled in the art, it is not necessary to describe it any further. The one shown in the drawings forms the subject-matter of a prior patent, No. 718,393, dated January 13, 1903; but any other known device of like character may be substituted. To hold each plate firmly in position while sticking the splints, I provide a cross bar or plate I , against which the back of the plates in sticking abuts. The lower edge of this plate is beveled off at j to prevent it from interfering with the travel of the plates. As soon as the plate at the foot of the incline has traveled up its own length, the plate next to it falls into position and follows it closely, and as the first and last row of perforations in each plate are distant from the approximate edges of the plate half the distance between the inner rows it will be seen that the rows of perforations follow each other as if they were all on one continuous plate, and it makes no difference which end of the plate is up, as both ends are alike. Should it be necessary at any time to discontinue the feeding of fresh plates, it is done by drawing out the slide E , which removes the plate at the foot of the incline from engaging with the drag-chains. After each plate has received its splints it travels a little distance farther, which carries it into the path of the main carrier A in proper relation thereto to have the carrying-lugs thereof engage into the slots a of the plate, and thereby transfer it to the main carrier. As the latter has a continuous motion and travels much faster than the subcarrier, the motion of which is intermittent and relatively slow, the plates will be spaced at intervals apart upon the main carrier. The plates have along their vertical edges marginal portions in which the slots a are formed near the

edges of the plate, each slot being somewhat larger at one end than the other, so as to facilitate the entrance of the lugs of the carrier if the slots should not accurately register with the lugs, and each plate is provided with two sets of such slots, so as to make the plate reversible end for end.

The plates are fed to the main carrier substantially in the plane of that carrier, and to insure the proper engagement of each plate therewith the plate is yieldingly held in position by a spring K , pressing against the back of the plate and allowing it to yield should a pair of lugs strike against the solid marginal portions until the lugs, which move faster than the plate, have caught up with the slots. This arrangement permits of stopping and starting the plate-feeding device irrespective of the movement of the main carrier.

All the parts forming the subject-matter of this invention may be structurally united into a single machine embodying all the various devices necessary for making matches, or the device may be constructed as an attachment to machines already in use.

With the use of my plate-feeding device I lose none of the advantages incident to the use of match machinery of the character described, while, on the other hand, I gain several advantages, which will be well understood by those skilled in the art without entering into a particular enumeration thereof.

While I have used the term "main carrier" to designate the carrier of what is ordinarily called the "dipping" device, I wish it understood that the term is intended to include any carrier designed to receive and carry the plates for treating the splints in any manner.

What I claim as my invention is—

1. In match machinery employing wholly independent plates for holding the splints, the combination with a vertical carrier, of means for successively feeding the plates to the carrier, comprising an inclined support arranged adjacent to the carrier and adapted to engage a number of plates at their lower edges and a pressure device adapted to bear against the back of the rearmost plate at the upper edge thereof.

2. In match machinery employing wholly independent plates for holding the splints, the combination with a vertical carrier, of means for successively feeding the plates to the carrier, comprising means for supporting a number of plates adjacent to the carrier and forming a suitable incline upon which the plates are adapted to slide upon their lower edges into the path of the carrier by the action of gravity and a pressure device adapted to press against the plates at their upper edges, whereby said plates are urged into the path of the carrier independently at both their upper and lower edges.

3. In match machinery employing wholly independent plates for holding the splints, the

combination with a vertical carrier, of means for successively feeding the plates to the carrier, comprising a plate-holding magazine having vertical sides for guiding the plates laterally into engagement with the carrier, a bottom inclined toward the carrier and upon which the lower edges of the plates are slidably supported and a pressure device adapted to bear against the upper edges of the plates only.

4. In match machinery employing wholly independent plates for holding the splints, the combination with a vertical carrier having guides in which the plates are carried, of a plate-holding magazine adjacent to the carrier and communicating with the space between the guides, means in said magazine for urging the plates forwardly into the space between the guides, and a yielding pressure device acting independently of said means to press against the backs of the plates after they have been moved upward from said magazine.

5. In match machinery employing wholly independent plates for holding the splints, the combination with a vertical carrier having guides in which the plates are carried, of a plate-holding magazine communicating with the space between the guides of the carrier, means for urging the plates into the space between the guides for their successive engagement with the carrier and a yielding pressure device acting independently of said means to press against the backs of the plates after they have been moved upward from the magazine.

35 6. In match machinery employing wholly independent plates for holding the splints, the combination with a vertical carrier having vertical guides in which the plates are carried, of means for successively feeding the plates to the carrier comprising an inclined support for supporting a number of plates upon their lower edges adjacent to the carrier, a pressure device adapted to bear against the upper edge of the rearmost plate, means for guiding the plates laterally into the space between the guides.

7. In match machinery employing wholly independent plates for holding the splints, of a vertical carrier composed of two endless chains revolving in a vertical plane common to both of them and forming between their adjacent vertical portions a space equal to the width of a plate in which the plates are adapted to be carried by the chains, a plate-holding magazine at the foot of the carrier-chains communicating with the space between the carriers and means for successively feeding the plates from said magazine into said space and a spring disposed above said feeding means to act against the backs of the plates.

65 8. In match machinery employing wholly independent plates for holding the splints, the combination with a vertical carrier having vertical guides in which said plates are carried, means at the base of the carrier for suc-

cessively feeding the plates to said carrier and comprising an inclined support upon which a number of plates are adapted to be supported upon their lower edges, a pressure device adapted to bear against the upper edge of the rearmost plate, a device for sticking rows of splints horizontally into said plates while in transit with said carrier and a cross-bar adapted to support the back of the plates in sticking.

9. In match machinery employing wholly independent plates for holding the splints, of a vertical carrier composed of two endless chains revolving in a vertical plane common to both of them and forming between their adjacent vertical portions a space equal to the width of the plates and in which the plates are adapted to be carried by the chains, means on one side of the vertical plane of the carrier-chains to successively supply the same with empty plates and means upon the opposite side of said plane to supply the plates with splints while in transit with the chains and a spring disposed above said feeding device to act against the backs of the plates.

10. In match machinery employing wholly independent plates for holding the splints, the combination of a vertical subcarrier, means at the base of said carrier for successively supplying the same with empty plates, and comprising an inclined support arranged adjacent to the carrier, a pressure device adapted to bear against the back of the rearmost plate at the upper edge only thereof, means for sticking splints in horizontal rows into the face of said plates while in transit with said carrier, and a main carrier having a vertical portion extending above the subcarrier and adapted to coöperate therewith to carry away the filled plates, said main carrier adapted to receive said plates with the sides into which the matches have been stuck.

11. In match machinery employing wholly independent plates for holding the splints, the combination with a main carrier composed of carrier-chains having carrier-lugs adapted to engage with and carry the plates, a portion of said main carrier arranged to travel in a substantially vertical path, of vertical guides below said vertical portion and adapted to guide the plates into engagement with the vertical portion of the main carrier, the rear portion of said guides near the upper end being made yielding, a subcarrier extending within a portion of said guides and adapted to elevate the plates within the guides, means for successively feeding empty plates at the base of the subcarrier and means for sticking rows of splints into the plates, while in transit with the subcarrier, into that side of the plates which are brought into engagement with the main carrier.

12. In match machinery employing wholly independent plates for holding the splints, the combination with a vertical subcarrier having means at the base for successively supplying

the same with empty plates and with means for sticking splints into the plates while in transit with said carrier, and a spring disposed above said feeding means to act against the backs of the plates of vertical guides extending above the subcarrier whereby the plates after having received the splints are released from engagement with the carrier and are free to be removed endwise from between said guides.

13. In match machinery employing wholly independent plates for holding the splints, the combination with a vertical subcarrier having means at the base for successively supplying the same with empty plates and means for supplying the plates with splints while in transit with said carrier, of vertical guides extending above the subcarrier and in which the plates are carried upwardly after receiving the splints without being in positive engagement with the subcarrier, and a main carrier adapted to carry the plates in the treatment of the splints and having a substantially vertical portion adjacent to the top of the guides and adapted to engage with the plates while in transit between said guides.

14. In match machinery employing wholly independent plates for holding the splints, the combination of a vertical subcarrier having means at the base for successively supplying the same with empty plates and means for filling said plates with splints while in transit with said subcarrier, of vertical guides in which said plates are carried by the subcarrier, and a main carrier wholly independent of the subcarrier and having a substantially vertical portion adjacent to the top of said guides, said guides extending some distance above the subcarrier and adapted to guide the plates into engagement with said vertical portion of the main carrier, the arrangement being such that if desired the filled plates may be removed by hand from between the guides, without being taken up by the main carrier, or the main carrier may be provided with filled plates from other sources.

15. In match machinery employing wholly independent plates for holding the splints, the combination with an independent and separately-organized device for filling the empty plates with splints and comprising a carrier in which the filled plates are carried upwardly between guides extending above the top of the carrier, whereby the filled plates after passing into that portion of the guides are released from engagement with the carrier and are removably held between the guides, of a main carrier wholly independent of the aforesaid device and having a substantially vertical portion adjacent to the top of said guides and adapted to engage with the plates while in transit between said guides upon that face of the plates into which the splints have been stuck, whereby said carrier is adapted to carry the plates for the treatment of the splints.

16. In match machinery employing wholly independent plates for holding the splints, the combination with a main carrier adapted to receive and carry the plates for the treatment of the splints, a subcarrier, a plate-holding magazine having inclined bottom and means for holding said plates against lateral displacement, means for applying splints horizontally to the plates, and a cross-bar against which the back of the plates abut in sticking. 75

17. In match machinery employing wholly independent plates for holding the splints, the combination with a main carrier adapted to receive and carry the plates for the treatment of the splints, a subcarrier, a plate-holding magazine having inclined bottom and means for holding said plates against lateral displacement, means for applying splints horizontally to the plate, and a cross-bar against which the back of the plates abut in sticking, 85 the lower edge of said bar being beveled.

18. In match machinery employing wholly independent plates for holding the splints, the combination with a main carrier adapted to receive and carry the plates for the treatment 90 of the splints, a subcarrier, a plate-holding magazine having inclined bottom and means for holding said plates against lateral displacement, means for applying splints horizontally to the plates, a cross-bar against which 95 the back of the plates abut, the lower edge of said bar being beveled, and a gravity-dog adapted to engage a plate below said cross-bar.

19. In match-machinery employing wholly independent plates for holding the splints, the 100 combination with a main carrier adapted to receive and carry the plates for the treatment of the splints, a subcarrier, a plate-holding magazine having inclined bottom and means for holding said plates against lateral displacement, means for applying splints horizontally to the plates, a cross-bar against which 105 the back of the plates abut, the lower edge of said plate being beveled, a gravity-dog adapted to engage a plate below said cross-bar, and a spring secured to the rear face of said cross-bar for yieldingly holding a plate in position. 110

20. In match machinery employing wholly independent plates for holding the splints for treatment, the combination with a main carrier for the plates, of a plate-feeding device therefor adapted to supply said main carrier with fresh plates as required for the continued operation of said carrier, said device being composed in part of a plate-holding 115 magazine having an inclined bottom upon which the plates rest with their lower edges free to slide to the foot of the incline, vertical side walls which hold said plates in position against lateral displacement, vertical stops on 120 said side walls at the foot of the incline for the plates to rest against, and a gravity-dog in the upper portion of the magazine adapted 125 to bear against the top portion of the plates of the magazine. 130

21. In match machinery employing wholly independent plates for holding the splints for treatment, the combination with a main carrier therefor, of a plate-feeding device for said main carrier adapted to automatically supply it with fresh plates as required for the continuous operation of said main carrier, said device composed in part of a magazine having an opening in front for the free insertion of the empty plates by hand, an inclined bottom for the lower edges of the plates to rest upon free to slide downwardly by gravity, vertical side walls to hold the plates in position against lateral displacement, vertical stops at the rear edges of the side walls adapted to retain the plates in vertical position in the magazine and a gravity-dog pivotally secured in the upper portion of the magazine adapted to coöperate in conjunction with the bottom of the magazine to feed the plates automatically against the vertical stops.

22. In match-making machinery, the combination with wholly independent plates and a main carrier adapted to receive and carry the plates for treating the splints, of a device for supplying said carrier automatically with fresh plates as required for the continuous operation of said carrier, said device composed in part of two endless carrier-chains arranged in a vertical plane common to both and provided with carrying-lugs adapted to carry the plates between the proximate parts of the carrying-chains with their vertical side edges in contact therewith, vertical guide-bearings in which said proximate parts of the carrier-chains travel, and a magazine adjacent to said carrier-chains having inclined bottom for the lower edges of the plates to rest upon to slide downward freely by gravity, and means for preventing lateral displacement of said plates and adapted to receive and hold empty plates and to automatically feed the same into the path of the carrier-chain and gravitating means secured in the upper portion of the magazine to coöperate in conjunction with said inclined bottom to feed the plates automatically and to hold them vertically.

23. In match machinery, the combination with wholly independent plates for holding the splints, and a main carrier adapted to receive and carry the plates for treating the splints, of a device for supplying said main carrier with fresh plates as required for the continuous operation of said carrier, said device composed in part of two endless carrier-chains arranged in a vertical plane common to both and adapted to carry the plates in the space between the two chains in contact with their side edges, and vertical guide-bearings for the plates while in transit with said carrier-chains, said carrier-chains having carrying-lugs spaced apart a distance equal to the length of the plates and the plates having their

upper and lower edges cut away to form recesses for said carrying-lugs. 65

24. In match machinery, the combination with wholly independent plates for holding the splints, and a main carrier adapted to receive and carry the plates for treating the splints, of a device for supplying said main carrier with fresh plates as required for the continuous operation of said carrier, said device composed in part of two endless vertical carrier-chains arranged in a plane common to both and having carrying-lugs adapted to carry the plates in a space between their proximate portions and in contact with the side edges of the plates, and a magazine adjacent to said carrier-chains and having vertical side walls forming a space between them equal to the width of the plates and communicating with the space between the carrier-chains, said magazine having inclined bottom for the lower edges of the plates to rest upon to slide downward freely by gravity, and means for preventing lateral displacement of said plates and adapted to receive and hold the empty plates and a gravitating dog disposed in the upper portion of said magazine for coöperation in conjunction with the inclined bottom of said magazine to feed said plates and hold their upper ends in position to automatically feed them into the space between the carrier-chains. 85

25. In match machinery, the combination with wholly independent plates for holding the splints and a main carrier for holding the plates in the treatment of the splints, of a device for automatically supplying the plates with splints and delivering them to the main carrier as required, said device embodying in part a subcarrier composed of two carrier-chains having carrier-lugs, portions of said chains being arranged in vertical guideways and adapted to receive and carry the plates in the space between them in contact with the side edges thereof, a stop having a beveled lower edge for engagement with said plates, and gravitating means for holding the upper ends of the plates in position. 95

26. In match machinery, the combination with wholly independent plates for holding the splints and a main carrier for holding the plates in the treatment of the splints, of a device for automatically supplying the plates with splints and delivering them to the main carrier as required for the continued operation of the same, said device composed in part of two carrying-chains, independent of the main carrier, and having a step-by-step motion, portions of said carrier-chains arranged in vertical guideways and adapted to receive and carry the plates between them in contact with the side edges thereof, said carrier-chains having carrying-lugs spaced apart a distance equal to the length of the plates. 110 115 120

27. In match machinery, the combination

with wholly independent plates for holding the splints and a main carrier for holding the plates in the treatment of the splints, of a device for automatically supplying the plates 5 with splints and delivering them to the main carrier as required for the continued operation of the same, said device composed in part of two carrying-chains, independent of the main carrier, and having a step-by-step motion portions of said carrier-chains arranged in vertical guideways and adapted to receive and carry the plates between them in contact with the side edges thereof, said carrier-chains having carrying-lugs spaced apart a distance 10 equal to the length of the plates, the plates having cut-away portions at the corners to form recesses for the carrying-lugs.

28. In match machinery, the combination with wholly independent plates for holding 20 the splints, and a main carrier for holding the plates in the treatment of the splints, of a horizontally-actuated device for automatically supplying the plates with splints in a horizontal direction and delivering them to the 25 main carrier as required for the continuous operation of the same, a subcarrier comprising two endless carrier-chains independent of said main carrier and arranged in a common vertical plane and having a step-by-step motion 30 to hold the plates in a vertical position during the insertion of the splints, and vertical guideways in which portions of said chains travel to receive and carry the plates in the space between them, said portions being of a length to carry a few plates at a time, and means against which the backs of the 35 plates abut during the process of sticking.

29. In match machinery, the combination with wholly independent plates for holding 40 the splints, of a device for automatically supplying the plates with splints and delivering them to a main carrier for the treatment of the splints, said device comprising a subcarrier composed of two carrier-chains arranged 45 in a common vertical plane and provided with carrying-lugs for the plates, spaced apart equal to the length of the plates, portions of said chains adapted to receive and carry the plates in a vertical path in the space between 50 them in contact with the side edges thereof and a main carrier composed of two carrier-chains having carrying-lugs, portions of said carrier-chains arranged to travel in the path of the plates of the subcarrier and adapted to 55 engage with and carry the plates in contact with the marginal portions along the side of the plates, said plates being adapted to engage with the carrying-lugs of the aforesaid carriers.

60 30. In match machinery, the combination with wholly independent plates for holding the splints, of a device for automatically providing the plates with splints and supplying them to a main carrier adapted to hold the

plates in the treatment of the splints, said device comprising a separate subcarrier having step-by-step motion and adapted to carry the plates in a vertical path, a magazine adapted to hold the empty plates and to automatically deliver the same to said subcarrier in the 65 travel of the same, a gravitating device disposed in the upper portion of the magazine to automatically engage the upper ends of the plates, a splint-sticking device adjacent to the path of the subcarrier and coöperating therewith to provide the plates with splints and a main carrier composed of two carrier-chains having continuous motion and provided with carrying-lugs adapted to engage with slots in the marginal side portions of the plates, portions 70 of said carrier-chains arranged to travel substantially in a vertical path contiguous to the path of the plates of the subcarrier and adapted to engage with and transfer the plates from the subcarrier to the main carrier. 75

31. In match machinery, the combination with wholly independent plates for holding the splints, of a device for automatically providing the plates with splints and supplying them to a main carrier for holding the plates 80 in the treatment of the splints, said device composed in part of a separate subcarrier having step-by-step motion and consisting of two carrier-chains having carrying-lugs for the plates, portions of said carrier-chains traveling in vertical guides and adapted to receive and to hold the plates between them in contact with the side edges thereof, a main carrier having continuous motion and consisting of two carrier-chains having carrying-lugs and 85 adapted to carry the plates in contact with the marginal side portions of the plates, portions 90 of which carrier-chains travel contiguous to the path of the plates on the subcarrier and adapted to transfer the plates from the same 95 to the main carrier and means at the point of transfer for yieldingly holding the plates against the main carrier. 100

32. In match machinery, the combination with independent splint-holding plates P, of the endless carrier-chains F having carrying-lugs spaced apart equal to the length of the plates and having proximate portions arranged in vertical guideways and adapted to receive and carry the plates in the space between the 110 same, and the plate-holding magazine C communicating with said space and provided with the vertical side walls b the inclined bottom c the slide E and the gravity-dog D. 115

33. In match machinery, the combination with independent splint-holding plates, of the endless carrier-chains F having carrying-lugs spaced apart equal to the length of the plates and having proximate vertical portions adapted to receive and carry the plates in the space 120 between the same, the plate-holding magazine communicating with said space and provided with means to automatically feed the plates 125

into said space, the splint-sticking device G, in the path of the aforesaid carrier, the cross-bar I opposite the splint-sticking device, the main carrier A provided with carrying-lugs 5 adapted to engage into marginal slots in the plates and the spring K yieldingly holding the plates in position at the point of transfer.

In testimony whereof I affix my signature in presence of two witnesses.

MARK A. SHELDON.
